BACK AND ARM SUPPORT CUSHION

William M. Emery, 44 Pittsford Way,
New Providence, N.J.

Filed Sept. 10, 1965, Ser. No. 86,943

Term of patent 14 years

(Cl. D3—9)

FIG. 1 is a front elevational view of a back and arm support cushion showing my new design, the back being similarly contoured, but without the fleur-de-lis or the arms; and

FIG. 2 is a side view thereof, the side opposite being a mirror image thereof.

I claim:

The ornamental design for a back and arm support cushion, as shown and described.
